UNITED STATES PATENT OFFICE.

BENJAMIN F. STAMM, OF HUNT, ILLINOIS.

SAFETY-RAZOR-BLADE HOLDER.

1,077,171.

Specification of Letters Patent.

Patented Oct. 28, 1913.

Application filed December 10, 1912. Serial No. 736,034.

To all whom it may concern:

Be it known that I, BENJAMIN F. STAMM, a citizen of the United States, residing at Hunt, in the county of Jasper and State of Illinois, have invented new and useful Improvements in Safety-Razor-Blade Holders, of which the following is a specification.

This invention relates to a holder for safety razor blades, whereby single or 10 double edged blades of different sizes and thicknesses may be clamped and held securely while the blade is being stropped, the object of the invention being to provide a simple, reliable, efficient and inexpensive 15 device of this character which will enable the clamped blade to be conveniently manipulated for stropping.

The invention consists of the features of construction, combination and arrangement 20 of parts hereinafter fully described and claimed, reference being had to the accompanying drawings, in which:

Figure 1 is a perspective view of the device showing a blade clamped thereto. 25 Fig. 2 is a side elevation of the device with the blade removed and with the handle shown partially in longitudinal section. Fig. 3 is a detail transverse section on the line 3-3 of Fig. 1, through the blade 30 and clamping member. Fig. 4 is a view showing the parts of the device separated.

In carrying my invention into practice I provide a handle 1, of any suitable material, which handle is provided at one end 35 with a receiving socket 2, adapted to receive the free ends of the arms of a blade clamping member 3.

The blade clamping member 3 consists of a single piece of heavy half round spring 40 steel wire, folded or bent upon itself, as at 4, midway of its length to provide arms 5 and 6, whose flattened surfaces face each other. These arms are adapted to normally spread apart under their natural resiliency 45 and to be drawn up and inserted at their free ends into the socket 2 of the handle, to hold said arms in clamping relation.

The arms are provided adjacent their connected ends 4 with clamping surfaces 7 and 50 have their free ends offset outwardly as at 8, so that the portions 7, when the arms are closed, may be drawn into parallel relation to clamp a safety razor blade 9, the construction being such that single or double 55 edged blades of different sizes and thicknesses may be readily and conveniently

clamped. It will be seen by reference to Fig. 1 that a blade 9 may be clamped and held securely between the surfaces 7, whereupon the operator by grasping the handle 1 may conveniently manipulate the blade to 60 strop the same without liability of injury to the operator. In inserting a blade the clamping member is withdrawn from the handle, the blade fitted between the surfaces 7, the arms of the clamping member drawn together, and the free ends of said arms then inserted in the socket, thus firmly 65 clamping the blade in position. To release the stropped blade it is simply necessary to withdraw the clamping member from engagement with the handle whereupon the arms 5 and 6 will spring apart and release 70 the blade.

The device may be employed for holding 75 either single or double edged blades. In its use for holding double or duplex blades, one of the edges of the blade is inserted between the jaws, which are wide enough to clamp the blade and at the same time 80 to cover and guard the clamped edge thereof. In this manner one edge of the blade may be sharpened and the blade may then be reinforced upon the holder and the other edge sharpened.

It will be seen that a device of the character described may be constructed and supplied at a comparatively low cost, and furnishes a simple and effective type of holder 85 for the purpose specified.

It will be observed that the arms 5 and 6 have outer flattened faces 10 which are beveled or rounded along their longitudinal edges, as at 11. By this construction the faces 10 are adapted to ride in contact with 95 the surfaces of a strop and hold the free edge of the blade at the proper angle or bevel for stropping it, while such formation of the arms adapts the device to be readily pivoted or turned on the strop for 100 the reverse strokes in stropping the opposite sides of the edge of the blade, the advantages of which will be apparent.

I claim:

A safety razor blade holder comprising a 105 uniformly wide strip of half-round spring metal bent or doubled upon itself at a median point, providing opposing blade clamping jaws integrally connected at one end and having their flattened surfaces in 110 juxtaposition, and arms extending from the free ends of said jaws, said jaws being di-

vergently arranged and adapted to normally spread apart by their resilient action, and being connected with the arms by outwardly extending oblique offsets, whereby the arms 5 are disposed at a greater angle of divergence than the jaws, and a handle having a socket adapted to receive and engage the free ends of said arms

and jaws together and dispose the jaws to clamp an interposed blade. 10

In testimony whereof I affix my signature in presence of two witnesses.

BENJAMIN F. STAMM.
